UNITED STATES PATENT OFFICE

EDWARD S. CHAPIN, OF PAWTUCKET, RHODE ISLAND, ASSIGNOR TO THE DELTEX COMPANY, A CORPORATION OF MASSACHUSETTS

APPARATUS FOR TREATING AND AGING FABRICS

Application filed June 18, 1930. Serial No. 462,048.

This invention relates generally to the treatment of fabrics composed of various materials, such as cotton, silk, rayon, wool or mixtures of said materials. It is particularly applicable to the treatment of fabrics where an aging action through a reduction of the dyes is desired. It especially relates to the treatment of fabrics having thereon vat color prints or dyes and to discharge prints or other fabrics where the conversion of the dyes or chemicals used in printing or dyeing, into fixed patterns and uniform colors is necessary.

This invention relates particularly to improved apparatus used in connection with the process of aging as described in the co-pending application of Edward S. Chapin and Areli H. Jacoby, Serial No. 462,047 filed concurrently on June 18, 1930, wherein a substantially closed chamber is supplied with an atmosphere of steam which excludes air and particularly oxygen so that the organic dyes are converted into the leuco bases.

Generally speaking, the present invention comprises means for supplying a definite and controllable amount of steam vapors at points between the runs of the fabric in an ager where the excess heat is more actively generated.

The means for accomplishing this object and its relation to the entire process of aging is more fully set forth in said co-pending application and it will not therefore be necessary to repeat the same at this point, except insofar as the means herein described may relate to the present claims.

It should be realized that when steam used in an ager is to any considerable extent superheated, it tends to rise in accordance with well known physical laws. This causes the superheated steam to accumulate between the runs of the fabric in the upper portion of the ager, particularly where the runs pass horizontally from one roll to another.

It is therefore one object of the present invention to supply not only water, but to introduce steam and to so control the action thereof between the runs of the fabric that the temperature will not be raised to an undesirable degree so as to produce the most

efficient aging action where the supply of the proper quantity and quality of steam has commonly been deficient. Water aprons have been described and illustrated in Patents Nos. 1,663,845 and 1,663,846, granted in the name of R. W. Jacoby, on March 27, 1928. These aprons enable water to be introduced between the runs of the fabric at points where the generation of objectionable high temperatures have occurred and enable the steam which has become superheated by the reactions of the dyes and the fabric, to absorb moisture and thereby increase the moisture content of such steam. This principle is availed of in the present improvements, but certain additions have been made which increase the efficiency of the aprons and permit greater control of the temperature and of the moisture content, thereby aiding in producing a substantially complete reduction and absorption of the dye upon and within the fibres of the fabric.

The following description taken in connection with the accompanying drawings sets forth a preferred form of apparatus in which the present improvements are embodied.

Referring to the drawings, Fig. 1 is a longitudinal sectional view of an improved ager constructed in its preferred form and including the subject matter of the present invention. Fig. 2 is a cross-sectional view thereof taken substantially upon the line 2-2 of Fig. 1. Fig. 3 is a transverse sectional view of the apron or casing taken substantially on the line 3-3 of Fig. 2, and Fig. 4 is an enlarged detailed sectional view of the upper portion of the device as shown in Fig. 3. Fig. 5 is an elevation of the right-hand lower portion of the ager shown in Fig. 2 indicating the pipe connections.

Referring to the drawings, the numeral 1 indicates a casing of sheet material, which forms the body of the ager and which is covered with a suitable heat insulating material 2, to prevent the escape of heat. At the upper left hand side of the ager is an opening 3 through which the cloth may enter and emerge from the interior of the ager. The opening 3 is provided with means to suck 100

away the steam which would tend to be discharged through said opening, said means preferably comprising a fan or other form of suction device 4, having a pipe 5 leading from the interior of a horizontal hood 6 which is adjacent the opening 3 through which the cloth passes when entering and emerging from the ager.

The top portion of the ager is provided with a plurality of hollow heating plates 7 which are adapted to be heated by steam in the well known manner.

The interior of the ager is provided with two series of rolls 8 and 8' over which the cloth to be aged passes successively in substantially parallel runs. After entering through the opening 3 as indicated in Fig. 1 and passing over the rolls 8 and 8' to the end of the ager, the fabric passes over rolls 9 which are provided to support the fabric as it returns toward said opening 3. The means for supplying moist steam under the necessary pressure and temperature to the main portion of the ager have been fully set forth and described in said co-pending application and will not be repeated here, since the subject matter of the present application has to do primarily with the aprons or casings and the pipes connected therewith for introducing steam and water at certain predetermined points.

Referring to Fig. 1 of the drawings, it will be seen that the first three pairs of the upper rolls 8 and two pairs of the lower rolls 8' are separated so as to provide wider spaces between the runs of the fabric than are provided between the subsequent rolls toward the right hand of the ager. This separation of the rolls results in two advantages. In the first place, the spaces above the horizontal runs of the fabric which pass between the lower rolls allow a rapid circulation of the steam vapors in the spaces between the upper rolls so that they may be easily withdrawn by the suction of the fan; consequently, the space below the runs passing between the upper rolls allows the introduction of aprons 13 which have been referred to above. These aprons are preferably constructed as indicated more particularly in Figs. 2, 3 and 4. It will be seen that there is a rectangular casing 13 preferably made of wire mesh screen material, such as copper, brass or other suitable metal. This is supported on suitable metallic frames 14 and is closed at the ends and top. A pipe 15 passes through the upper portion of this casing, which pipe is preferably slotted at its upper side as indicated at 16. This pipe is supplied with water from the main water supply pipe 17 and in the pipe connections of valves 18 for controlling the flow of water.

The pipe 15 has suitable supports 19 on the walls of the casing 1 and since the said supply pipe passes through holes in the casing

13, the casing is thereby supported in vertical position. Collars 20 are placed upon the pipe 15 to prevent the casing 13 from sliding longitudinally thereon and are preferably attached to said casing by soldering or otherwise.

The casing 13 is preferably composed of three or four layers of wire mesh so as to more effectively equalize and distribute the flow of moist vapors therethrough, as will hereafter be more fully described. The left hand manifold 10 has a series of nipples which connect with the valves 21 and the latter are connected with T pipe connections 22.

One outlet of these T connections carry pipes 23 which connect with vertical pipe 24. These pipe connections and the valves are preferably of the two in h size. The other outlets of the T connections 22 carry pipes 25 having valves 26, which connect with a live or high-pressure steam manifold 27, the purpose of which will be more fully described hereafter.

The upper portion of the pipes 24 carry three more or less, horizontal branches 28, 29 and 30, the ends of which are closed as indicated in Figs. 2 and 4, and each of which are provided with series of perforations or holes through which the steam may escape. These holes are preferably more numerous in the upper branches 30, less numerous in the branches 29 and still less numerous in the branches 28. These pipes as indicated in Figs. 1 and 3 are located between the two sides of the wire mesh apron or casing 13 and 15. The valves 21 are provided for the purpose of controlling the flow of the steam to the pipes 23 and the branches 29 and 30 connected therewith.

It should be noted that there are three sets of casings 13 and each has a corresponding steam supply pipe located between the sides thereof and a water pipe 15 located at the top thereof. Obviously, the number of these pipes and casings may be varied according to the requirements of a particular ager designed for a particular or special use. In an ager in which three or more aprons are provided, any number of them may be placed in operation or may be made inactive as desired according to whether or not the steam and water are admitted thereto.

The operation of this portion of the ager will now be described:

Assuming that the ager has been started, and the internal atmosphere thereof generally provided with the necessary amount of steam vapor through the steam supply pipes 15 at the bottom of the ager, the passage of the fabric through the opening 3 and over the rolls 8 and 8', as indicated in Fig. 1, will cause the conversion of the dyes to start immediately, upon coming in contact with the

warm moist vapors of the ager. This conversion, owing to the physical and chemical reactions, which take place within the ager, produces a considerable amount of excess heat, as has been explained in the prior patents above mentioned. This production of excess heat occurs at times with almost explosive force in the forward part of the ager soon after the cloth enters the same, and at this point, the neutralization, absorption and dissipation of the heat is required to a greater extent. This is the reason that the special means in the form of aprons and wider spaces between the runs above described have been provided. The flow of water through the pipes 17 and 15 allows the water to escape through the slot 16 at the top of the pipe 15, and it accordingly runs or trickles downward over the sides of the pipe in a greater or less volume, according to the adjustment of the valve 18. The steam pipes 33, 23, 24, 28, 29 and 30 supply steam, preferably of comparatively low pressure and of the required moisture content to the space between the sides of the casing or apron 43, and thereby produces a continuous flow of vapors outward through the sides of the casing or aprons.

The water, which, has above been referred to as flowing downward from the pipes 15, will therefore come in contact with the steam escaping through the holes in the pipes 28, 29 and 30, and will cause vaporization of the latter, which action will still further increase the saturation or water content of such steam vapors.

If steam is not allowed to flow through the pipes 28, 29 and 30, they will act as baffles and distribute the water upon the apron 15.

Ordinarily the temperature of the water introduced to the pipe 15 is comparatively low, that is, little if any above atmospheric temperature, but obviously it may be raised to a higher point, if deemed advisable under certain conditions. The steam is therefore much cooler than steam that could be introduced by allowing it to expand entirely outside of the ager.

The action of this moist steam between the sides of the apron or casing is an expansive one, and therefore tends to pass through the mesh of the wire screen, until it reaches the fabric or at least reaches the vicinity of any superheated vapors which may be produced on account of the chemical and physical reactions occurring within the fabric and dyes.

If it be necessary to use more dry or high pressure steam than that supplied through the manifolds 33, then the valves 21 may be closed and the valves 25 opened. This will allow live steam from the manifold 27 to pass into the pipes 23, 24, 28, 29 and 30. Water from the pipe may be allowed to mix with such steam if its temperature and dryness be too great for the aging required ad-

jacent the aprons 13. If not, the water may be cut off.

It will be thus appreciated that the means and method for supplying at will more or less dry vapors or very highly saturated vapors directly to the points where they are most active, enables the neutralization, absorption and dissipation of the excess heat produced to take place very efficiently and accurately, in accordance with the amount of temperature and moisture required.

It will also be appreciated that by reason of the control of the water supply, and of the steam supply through a manipulation of the valves 18, 21 and 26, both the water and the steam can be controlled to a nicety, thereby enabling the temperature to be fixed at any desired point, that may be necessary for a particular kind of goods being treated, and this temperature may be set substantially at any point between 212 or 213° and 235 or 240° Fahrenheit, and may be maintained at such point substantially continuously during the period of run of the ager, independently of the variations in the conditions which have ordinarily existed in the commonly used agers.

The apparatus thus provided is therefore extremely flexible and capable of being manipulated at will to produce the best results. This has been determined by actual practical operation of an ager, provided with the apparatus herein described, and it has been found to be eminently superior to any other form of aging device or any process heretofore devised for that purpose.

This process and apparatus has been found to practically solve the problems of the accurate control and maintenance of definite temperatures within an ager, and has enabled results to be obtained in processes of aging both in the depth of color and economy of dyes that were never before accomplished or thought possible.

Having thus described this form of my invention, what I claim and desire to protect by Letters Patent is:

1. In combination with an apparatus for treating or aging fabric which includes an aging box or chamber, two series of rolls over which the fabric is adapted to pass, to form spaces between the runs thereof, an apron of porous material, located in a zone between the runs of fabric formed by said rolls, and means for introducing vapors of an evaporable liquid within the interior of said apron.

2. In combination with an apparatus for treating or aging fabric which includes an aging box or chamber, two series of rolls over which the fabric is adapted to pass, to form spaces between the runs thereof, an apron of reticulated material, located in a zone between the runs of fabric formed by said rolls, and means for introducing vapors of an

- evaporable liquid within the interior of said apron.
3. In combination with an apparatus for treating or aging fabric which includes an aging box or chamber, two series of rolls over which the fabric is adapted to pass, to form spaces between the runs thereof, an apron of wire screening located in a zone between the runs of fabric formed by said rolls, and means for introducing vapors of an evaporable liquid within the interior of said apron.
4. In combination with an apparatus for treating or aging fabric which includes an aging box or chamber, two series of rolls over which the fabric is adapted to pass to form spaces between the runs thereof, an apron of porous material located in a vertical zone between the runs formed by said rolls, means for introducing steam vapors within the interior of said apron, and means for varying the moisture content of said vapors.
5. In combination with an apparatus for treating or aging fabric which includes an aging box or chamber, two series of rolls over which the fabric is adapted to pass to form spaces between the runs thereof, an apron of reticulated material located in a vertical zone between the runs formed by said rolls, means for introducing steam vapors within the interior of said apron, and means for varying the moisture content of said vapors.
6. In combination with an apparatus for treating or aging fabric which includes an aging box or chamber, two series of rolls over which the fabric is adapted to pass to form spaces between the runs thereof, an apron of wire screening located in a vertical zone between the runs formed by said rolls, means for introducing steam vapors within the interior of said apron, and means for varying the moisture content of said vapors.
7. In combination with an apparatus for treating or aging fabric which includes an aging box or chamber, two series of rolls over which the fabric is adapted to pass to form spaces between the runs thereof, an apron of reticulated material located in a vertical zone between the runs of fabric formed by said rolls, and means for forming moist steam vapors within the interior of said apron.
8. In combination with an apparatus for treating or aging fabric which includes an aging box or chamber, two series of rolls over which the fabric is adapted to pass to form spaces between the runs thereof, an apron of reticulated material located in a vertical zone between the runs of fabric formed by said rolls, means for introducing moist vapors within said apron, and means for introducing an evaporable liquid within said apron.
9. In combination with an apparatus for treating or aging fabric which includes an aging box or chamber, two series of rolls over which the fabric is adapted to pass to form
- spaces between the runs thereof, an apron of reticulated material located in a vertical zone between the runs of fabric formed by said rolls, means for introducing steam vapors within the interior of said apron, and means for introducing water within said apron to contact with said steam vapors.
10. In combination with an apparatus for treating or aging fabric which includes an aging box or chamber, two series of rolls over which the fabric is adapted to pass, certain of said rolls being separated to form a space between the runs of said fabric, an apron of reticulated material located in the vertical zone between said runs, a pipe having openings for introducing steam vapors within the interior of said apron and a pipe within said apron and having an outlet whereby water is caused to contact with the steam vapors from said first mentioned pipe, said aprons causing a uniform distribution of said vapors through said material and into the spaces adjacent said runs.
- In witness whereof I have signed my name this 29th day of May, 1930.
- EDWARD S. CHAPIN.
